UNITED STATES PATENT OFFICE.

WILLIAM H. McNUTT, OF NEW YORK, N. Y., ASSIGNOR TO CARRIE EMMA OWEN, OF FRANKLIN, NEW YORK.

CAN-CLOSURE.

1,114,165.

Specification of Letters Patent.

Patented Oct. 20, 1914.

Application filed September 6, 1913. Serial No. 788,420.

To all whom it may concern:

Be it known that I, WILLIAM H. McNUTT, a citizen of the United States, and resident of New York city, in the county of New York and State of New York, have invented certain new and useful Improvements in Can-Closures, of which the following is a specification.

The object of this invention is to provide an improved arrangement of self-closing valve for cans or receptacles intended for the storage of inflammable liquids, in which the valve is normally seated under spring pressure, and when opened and released will at once return to closed position; which valve will have its seat-engaging portion formed of soft yielding material such as soft rubber to insure a perfectly tight closure preventing any possible escape of either liquid or vapor from the can.

A further object of the invention is to provide with such a form of valve, convenient means for grasping the valve member to open the valve and hold it in open position; which arrangement will provide means for strongly retaining the yieldable seat portion of the valve in the required position, and which further will permit the seat portion of the valve to be easily removed and another substituted.

In the accompanying drawing illustrating one embodiment of my invention, Figure 1 shows the upper portion of a can with my invention applied thereto, partly in section, and partly in elevation; Fig. 2 is a section taken through the valve at right angles to Fig. 1; and Fig. 3 shows the valve in open position.

In the drawing I show a can 3 having its top 4 provided with an opening at which is suitably secured a bushing 5. This bushing is shown as externally threaded to screw into an internally threaded sput 6 that is secured to the top 4 by suitable means such as rivets. The bushing 5 projects some distance above the can top, and at its upper end is provided with a valve seat, by having the end portion flaring as shown at 7.

A filler tube 8 of flame-proof construction, preferably formed of finely perforated sheet metal such as brass, is secured at its upper end in the bore of the bushing 5 at the lower portion thereof, and projects a considerable distance down into the can. The lower end 55 of the tube 8 is shown as closed by a cap 9

which is fitted thereon, the said cap being provided with a central opening 10. Inside of the tube 8 is placed a valve rod 12, that projects loosely through the opening 10 in the cap 9 for some distance, so as to permit its upper end portion to be brought adjacent the sides of the tube and bushing.

A coil spring 13 is arranged around the lower extension of the valve rod 12 with its upper end in engagement with the lower face of the cap 9 and its lower end secured to the rod 12, being shown as resting on nuts 14 on the threaded end portion of the rod. On the upper end of the valve rod 12 is mounted a yielding valve member 15 of soft rubber or other suitable yielding material, which is held normally in engagement with the seat portion 7 of the bushing 5 by the tension of the coil spring 13, which latter is put under compression by the nuts 14 to draw the rod 12 downward, the said valve having an approximately hemi-spherical shape. Instead of mounting this valve 15 directly on the rod 12, I provide a hinged connection with the rod, so that when the valve is raised from its seat by suitable means, such as a bail 16, the valve can be swung on the rod and drawn to one side to assist in holding it open while the can is being emptied.

I provide a head 17 that is pivoted to the end portion of the valve rod 12, and from the upper face of the head projects a stem 18 that passes through the bore of the valve 15, and is threaded at its upper end to receive a nut 19 that will serve to lock the valve on the head as shown.

For the purpose of providing an anchorage for the bail 16 on the valve, and also to properly protect the top of the soft rubber valve 15, I provide a cap 21 having a central hole to receive the stem 18 of the valve, the flange 22 of the cap extending a short distance around the upper edge of the valve 15. It will be understood that the tightening of the nut 19 will serve to confine the valve between this cap 21 and the head 17, whereby only the seat engaging portion of the valve 15 is exposed, and the valve, especially its upper marginal portion, is protected and strengthened by said cap. On the upper face of the cap 21 I arrange apertured ears 23 and 24, in which is pivotally mounted the bail 16; and these ears are so arranged that when the cap is secured in position, the axis on which the bail swings is 110

parallel to the axis on which the head 17 swings on the valve rod 12.

In the use of the device, to open the valve the bail 16 is grasped by the operator and pulled upwardly and also laterally to either side in the direction in which the bail can swing, as indicated in Fig. 3. This will cause the valve member to swing on the rod and in the same direction since these two axes are parallel. This upward movement of the valve rod will increase the tension of the spring 13, and obviously as soon as the valve is released it will be returned to normal position; and being of soft rubber, the valve will yield to allow for any unevenness of the seat and will insure a very tight closure.

The coil spring 13 being located below the bottom of the filler tube, will be protected from any injury; and being usually immersed in the liquid in the tank will be protected from any chemical action of the air. This spring will also serve to retain the cap 9 closing the lower end of the filler tube in its proper position, without other fastening means for the cap being needed.

When the soft rubber valve seat becomes worn, it can be very easily and quickly replaced, by simply unscrewing the nut 19 and removing the valve cap and bail. During this operation the stem 12 can be grasped by the fingers or a suitable tool or device.

Having thus described my invention, what I claim is:

1. The combination of a can provided with a bushing secured in an opening in the can top and having a valve seat at its upper projecting end, a flame-proof tube projecting down from said bushing a considerable distance into the can, a cap closing the lower end of the tube and provided with a central opening, a valve rod in the tube projecting down through said cap opening, a coil spring on the rod below the cap fast to the lower end of the rod and having its upper end engaging the lower face of the cap to draw the rod downward, a globular valve hinge on the upper end portion of said rod and retracted to seat on the said valve seat by said spring and normally retained seated thereby, and a bail hinged to the top of the valve with its axis parallel with the axis of the valve.

2. The combination of a can provided with a bushing secured in an opening in the can top and having a valve seat at its upper projecting end, a flame-proof tube projecting down from said bushing a considerable distance into the can, a cap closing the lower end of the tube and provided with a central opening, a valve rod in the tube projecting down through said cap opening,

a coil spring on the rod below the cap fast to the lower end of the rod and having its upper end engaging the lower face of the cap to draw the rod downward, a head hinged to the upper end of the rod and having a threaded stem projecting upward, a globular valve having a bore through which the threaded stem projects, a cap engaging the top of the globular valve and having an opening through which said threaded stem projects, a nut on the threaded stem confining the valve between the second-named cap and head, and a bail hinged to the top face of the valve cap. 75

3. The combination of a can provided with a bushing secured in an opening in the can top and having a valve seat at its upper projecting end, a flame-proof tube projecting down from said bushing into the can, a closure for the lower end of the tube, a valve rod in the tube, a spring connecting the rod with the lower end of the tube and arranged to draw the rod downward, a head hinged to the upper end of the rod and having a threaded stem projecting upward, a globular valve having a bore through which the threaded stem projects, a cap engaging the top of the globular valve and having an opening through which said threaded stem projects, a nut on the threaded stem confining the valve between the said cap and head, and a bail hinged to the top face of the valve cap. 80

4. The combination of a can provided with a bushing secured in an opening in the can top and having a valve seat at its upper projecting end, a flame-proof tube projecting down from said bushing a considerable distance into the can, a cap closing the lower end of the tube and provided with a central opening, a valve rod in the tube projecting down through said cap opening, a coil spring on the rod below the cap fast to the said cap and having its upper end engaging the lower face of the cap to draw the rod downward, a head hinged to the upper end of the valve rod and having a threaded stem projecting upward, a globular valve having a bore through which the threaded stem projects, a cap engaging the top of the globular valve and having an opening through which said threaded stem projects, a nut on the threaded stem confining the valve between the second-named cap and head, and a bail hinged to the top face of the valve cap with its axis parallel with the axis of the valve. 90
